UNITED STATES PATENT OFFICE

2,615,256

CONTOUR GAUGE

Harry L. Olson, Minneapolis, Minn., assignor to
 Ckola Company, Minneapolis, Minn., a corporation of Minnesota

Application May 17, 1951, Serial No. 226,788

2 Claims. (Cl. 33—175)

1

My invention relates to contour gauges and has for an object the provision of means whereby the contour of a given line or article may be quickly and easily copied.

Another important object of my invention is the provision of a contour gauge which is quickly and easily adjusted to a given contour and locked in its adjusted position.

A still further object of my invention is the provision of a contour gauge as set forth which may be stored in a minimum of space and which in use may be inserted into areas of relatively small dimension.

Another object of my invention is the provision of a contour gauge comprising a plurality of contour indicating fingers in side-by-side relationship wherein novel means are provided for maintaining said fingers in side-by-side parallel relationship.

Still another object of my invention is the provision of a contour gauge as set forth which is relatively simple and inexpensive to manufacture, which comprises a minimum of different parts, which is efficient in operation, and which is rugged in construction and durable in use.

Other highly important objects and advantages of my invention will become apparent from the following detailed specification, appended claims, and attached drawings.

Referring to the drawings which illustrate the invention and in which like characters indicate like parts throughout the several views:

Fig. 1 is a view in side elevation of my novel contour gauge, some parts being broken away and some parts shown in section;

Fig. 2 is a view in end elevation as seen from the left to the right with respect to Fig 1; and

Fig. 3 is a view in end elevation as seen from the right to the left with respect to Fig. 1.

Referring with greater detail to the drawings, my novel contour gauge is shown as comprising a plurality of elongated plate-like contour indicating fingers 1 that are mounted in side-by-side parallel relationship on a mounting member 2. Each of the fingers 1 is provided intermediate its opposite ends 3 and 4 with a slot 5 which extends longitudinally of the finger 1 and through which the mounting member 2 projects.

The mounting member 2 is in the nature of a plate-like bar and is of a length to extend laterally outwardly beyond the plates 1 and carries a pair of cooperating clamping elements in its opposite ends. One of the clamping elements is in the nature of a flange or plate 6 riveted or otherwise rigidly secured to the adjacent end of

2

the mounting bar 2 and the other of said clamping members comprises a bifurcated cam-acting lever 7 pivotally mounted on the opposite end portion 8 of the mounting bar by means of a headed pivot pin or the like 9. The lever 7 is formed to provide a pair of cam-acting surfaces 10, one of which is shown, which are eccentric to the axis of the pivot pin 9 whereby, when the lever 7 is moved to its dotted-line position of Fig. 1, the several indicator fingers 1 are free to move longitudinally with respect to each other and to the mounting member 2. However, when the lever 7 is moved to its full-line position of Fig. 1, the contour indicating fingers 1 are compressed therebetween and the flange 6 and frictionally locked against said longitudinal movements. A rectangular washer 11 is mounted on the mounting bar 2 between the lever 7 and the adjacent finger 1 and serves to provide a wearing surface against which the cam surfaces 10 are adapted to bear. The mounting bar 2 is substantially of the same thickness as the width of the slots 5 in the several fingers 1 less proper working clearance, so that when the clamping lever 7 is moved to its finger releasing position, indicated by dotted lines in Fig. 1, the several fingers are free to move longitudinally with respect to the mounting bar 2. The bar 2 is, however, of sufficient width to prevent rotation thereof with respect to the fingers 1 so that the parallel relationship of the fingers is maintained irrespective of the longitudinal displacement of some of the fingers with respect to others thereof.

It will be noted, by reference to Figs. 2 and 3, that the clamping elements 6 and 7, the pivot pin 9, and the washer 11 are of widths not exceeding the width of the several fingers 1. This arrangement not only permits the entire device to be stored in a relatively confined area in the user's tool box or the like, but also permits determination of surface contours in restricted areas. The end portions 4 of the several fingers 1 are reduced in width, as indicated at 12, to further permit entrance thereof into restricted areas and to enable the user to determine the contour of a given article or line with greater accuracy and with a minimum of effort.

When it is desired to determine the contour of a given object, the user moves the lever 7 to its dotted-line position in Fig. 1 and holds the gauge substantially perpendicular to the surface to be gauged with the ends 4 of the fingers abutting said surface. The several fingers 1 are manipulated so that the ends 4 of each thereof contact the surface to be gauged or determined

after which the lever 7 is moved to its locking full-line position of Fig. 1. The contour formed by the position of the fingers 1 may then be compared to a layout or pattern, or the gauge may be placed upon a sheet of paper or other material and the contour inscribed upon the paper with a pencil, using the ends 4 of the fingers 1 as a guide for the pencil.

My invention has been thoroughly tested and found to be completely satisfactory for the accomplishment of the objectives set forth; and, while I have shown and described a commercial embodiment of my novel contour gauge, it will be understood that the same is capable of modification without departure from the spirit and scope of the invention as defined in the claims.

What I claim is:

1. A contour gauge comprising a plurality of contour indicating fingers mounted in side-by-side parallel relationship, said fingers being of uniform dimensions and each having a longitudinally extended slot intermediate its ends, a plate-like mounting bar extending transversely through said slots, said mounting bar being of a thickness only slightly less than the width of said slots, whereby to permit limited longitudinal sliding movements of said fingers with respect to said bar and to each other and having sufficient width to prevent rotation thereof in said slots, and cooperating clamping elements on the opposite ends of said mounting bar laterally outwardly of said fingers, one of said clamping elements comprising a flange rigidly mounted on

5 said bar and engageable with the adjacent finger, the other of said clamping elements including a cam-acting lever pivotally mounted on the other end of the bar, said lever being movable in one direction of pivotal movement to permit longitudinal sliding movements of said fingers with respect to each other and to the mounting bar, and in the opposite direction of pivotal movement to compress said fingers together whereby to frictionally lock the same against said sliding movements.

10 2. The structure defined in claim 1 in which the several fingers are reduced in width at one end to permit entrance thereof into restricted areas.

15 HARRY L. OLSON.
